The ornamental design for a tomosynthesis device, as shown and described herein.

DESCRIPTION

FIG. 1 is a perspective view of a tomosynthesis device in accordance with the present invention.

FIG. 2 is a front elevational view of the tomosynthesis device of FIG. 1.

FIG. 3 is a back elevational view of the tomosynthesis device of FIG. 1.

FIG. 4 is a right side elevational view of the tomosynthesis device of FIG. 1; and,

FIG. 5 is a left side elevational view of the tomosynthesis device of FIG. 1.

The broken lines in the drawing views are included for the purpose of illustrating portions of the tomosynthesis device that form no part of the claimed design.
